US00D988864S

(12) **United States Design Patent** (10) **Patent No.:** **US D988,864 S**
Dunn et al. (45) **Date of Patent:** **** Jun. 13, 2023**

(54) **CAN LID**

- (71) Applicant: **Silgan Containers LLC**, Woodland Hills, CA (US)
- (72) Inventors: **David Dunn**, Palmyra, WI (US); **Elizabeth A. Metzger**, Wauwatosa, WI (US); **John Schindewolf**, Rochelle, IL (US); **Alvin Widitora**, Los Angeles, CA (US); **Dave Wood**, Oconomowoc, WI (US); **Seth Moore**, Oconomowoc, WI (US); **Andrew Palumbo**, Conshohocken, PA (US)
- (73) Assignee: **Silgan Containers LLC**, Woodland Hills, CA (US)
- (**) Term: **15 Years**
- (21) Appl. No.: **29/819,670**
- (22) Filed: **Dec. 16, 2021**

Related U.S. Application Data

- (62) Division of application No. 29/761,485, filed on Dec. 9, 2020, now Pat. No. Des. 939,956, which is a division of application No. 29/712,555, filed on Nov. 8, 2019, now Pat. No. Des. 907,489, which is a division of application No. 29/626,050, filed on Nov. 14, 2017, now Pat. No. Des. 879,609.
